UNITED STATES PATENT OFFICE.

GEORGE A. KNOX, OF WASHINGTON, DISTRICT OF COLUMBIA, ASSIGNOR TO KENNETH ALFRED KNOX, OF CAMBRIDGE, MASSACHUSETTS.

TORPEDO.

1,163,158.

Specification of Letters Patent.

Patented Dec. 7, 1915.

Application filed January 7, 1915. Serial No. 927.

To all whom it may concern:

Be it known that I, GEORGE ALFRED KNOX, a citizen of the United States, residing at 3920 Fifth street northwest, Washington, District of Columbia, have invented new and useful Improvements in Torpedoes, of which the following is a specification.

My invention relates to improvements in automobile submersible torpedoes used in offensive and defensive warfare and its objects are: The removal from the outside of the torpedo of all trip levers, lugs, or other projections for starting the controlling and the actuating mechanism. The provision of starting mechanism inclosed within and attached to the torpedo afterbody shell, or the bulkheads therein provided, for operating the "torpedo starting piston" thereby admitting "flask air" simultaneously to the gyro spinning mechanism and to the reducing valve connected to the superheater of the turbine actuating mechanism. The provision of a starting mechanism carried within the torpedo body and properly positioned therein for operative action through an externally admitted impulse force. The provision of a mechanism inclosed within the torpedo case, body or shell for starting the gyroscope spinning mechanism and the torpedo turbine driving mechanism. The provision of a device by which the gyro spinning and torpedo propelling mechanism will be started, invariably before the impulse is given which discharges the torpedo from its spoon, tube or carrier. The provision of mechanism whereby the liability of discharging a "dead" torpedo is fully overcome. To simplify the starting of the gyro spinning and the torpedo propelling mechanisms. To greatly reduce the cost of construction of mechanism for the purpose stated.

Other objects and advantages of my invention will appear as the description proceeds.

I attain these objects by means illustrated in the accompanying drawings, in which:

Figure 1, illustrates a transverse section of a torpedo showing, in section, my improvement applied thereto. Fig. 2 is an elevation of my improvement, partly in section, looking in the direction indicated by

the arrow in Fig. 1. Fig. 3 is a modification showing my improvement adapted to operate a torpedo of a different type. Fig. 4 is a sectional view of a modification showing the gyro setter combined with my improved starting mechanism. Fig. 5 is an elevational view of a modification in which the supply of compressed air for operating my starting mechanism is carried in a receiver provided for that purpose and inclosed within the body of the torpedo. Fig. 6 is a sectional view taken on line VI on Fig. 5 and looking in the direction there indicated by an arrow. Fig. 7 is a sectional view taken on line VII-VII of Fig. 5, parts being removed, and looking in the direction there indicated by arrows. Fig. 8 is a plan view of a modification in which the torpedo "flask air" is utilized to operate my improved starting mechanism. Fig. 9 is a sectional view taken on line IX-IX of Fig. 8, looking in the direction there indicated by the arrows. Fig. 10 is a sectional view taken on line X-X of Fig. 8, looking in the direction there indicated by the arrows.

In the preferred form shown in Figs. 1 and 2 each element is designated by its respective reference character in both views and in the four modifications the same reference characters are used, preceded by one hundred, two hundred, three hundred, and four hundred respectively, to designate the corresponding elements.

The numerals 1 indicate parts of the torpedo case, shell or body, to the interior of which my improvement is secured by watertight connections in any suitable manner.

The number 4 designates a valve casing provided with a packing gland 5. To the inner end of casing 4 a casing extension 6 is secured, having on its interior surface a stop 7 which limits the movement of a valve plug 8 when shoulder 9 on said valve plug 8 and stop 7 engage. The normal position of valve plug 8 is that wherein shoulder 9 and stop 7 are in engagement. The purpose of spring 10 is to hold valve plug 8 in normal position. Expansion spring 10 should be sufficiently powerful to overcome the water pressure at the depth the torpedo is intended to travel or to overcome the tor-

pedo afterbody ejecting pressure. Cap 11 is suitably secured upon the free end of casting extension 6. Valve plug 8 has a solid head 12 at its outboard end and an extension or cage 13 extends inwardly from said head 12. On the free end of extension or cage 13 shoulder 9 is located.

Head 12, shoulder 9, and plug extension or cage 13 may be made integral or they 10 may be made separately and assembled. Expansion spring 10 is located inside plug extension or cage 13. One end of spring 10 bears against head 12 and the other end engages spring seat 14 on the inside of cap 15 11. It is not essential that valve plug 8 shall be hollow, as shown, but such construction makes the device more compact and reduces weight. It is obvious plug 8 might 20 be solid throughout its entire length and spring 10 might engage the end of the plug. In that case, extension 6 would be constructed of sufficient length to accommodate spring 10 which, in the construction illustrated, is housed inside valve plug extension or cage 13.

At a suitable point on valve casing 4 an extension 15, having an air passage therethrough, is located. The air passage through extension 15 communicates with the inside 30 of valve casing 4 when unobstructed by plug 8. One end of pipe 2 is connected with extension 15 and the other end of pipe 2 is connected with a check valve box 16 in communication with cylinder 3. Piston 17 is located in cylinder 3. A piston rod 18 is connected to the piston 17 and extends through an opening provided therefor in cylinder head 19 which has preferably a water tight stuffing box for piston rod 18. An expansion spring 20 surrounds piston rod 18. One end of spring 20 bears upon piston 17 and the other end bears upon cylinder head 19. The normal position of piston 17 and piston rod 18 is that in which piston 17 is in engagement with stop pin "a" in cylinder 3. Cylinder 3 is suitably connected to the torpedo and so located that piston rod 18, when projected, will strike "starting pin" "P". Pin "P" is a part of the torpedo and by 40 means of intermediate elements, when thrust forward, actuates, the gyro spinning and torpedo propelling mechanisms in a manner well known to those skilled in the art.

Check valve 21 is hinged at 22 in valve box 16 in such a manner that, when air rushes through either pipe 2, valve 21 will be swung over and instantly seal the inlet from the pipe 2 leading to the valve mechanism not in use.

Connected to extension 15 is another extension 23 having an air passage 28 therethrough in communication with the air passage in extension 15 and the exterior of the torpedo, but this passage is normally kept

closed by a conical relief valve 24 retained 65 on its seat by an expansion spring 25 which encircles the stem 26 of valve 24 and the stem guide 27. There are several orifices 29 through stem guide 27 which provide a passage way from the pipe system to the exterior of the torpedo. This relief valve is necessary to reduce the pressure in the pipe system so that spring 20 can withdraw piston rod 18 from engagement with starting pin "P" and thereby permit the closure of 70 the flask valve previously opened by starting pin "P". Through alining opening in the torpedo tube, the torpedo spoon and the torpedo body registering with valve plug 8 a nozzle 30 which is a part of a conduit leading to a source of power, may be inserted.

The specific form of nozzle forms no part of this invention. It is a part of another invention for which an application will be filed in the near future. In this application I 85 merely illustrate and describe a nozzle which operates my starting device successfully. Nozzle 30 is composed of a tube in which a longitudinally movable plunger valve 31 is telescopically assembled.

Plunger valve 31 has a solid end so formed that when in normal position (shown at the left in Fig. 1) the outer tube of nozzle 30 and the solid end of plunger valve 31, together form a cone adapted to be seated in a correspondingly shaped conical cavity in the outboard end of valve plug 8. On the inside of the outer tube of nozzle 30 there is a shoulder 33, and upon the exterior of the inner end of plunger valve 31 there is a shoulder 32. Interposed between the shoulders 32 and 33 and surrounding plunger valve 31 is an expansion spring 34, the function of which is to maintain the normal position of these parts hereinbefore explained.

In Fig. 4 I have shown two valve mechanisms, one on the starboard side of the torpedo the other on the port side of the torpedo. These valve mechanisms are identical in construction and each of them is connected by a pipe 2 to the piston cylinder 3.

It is to be understood that my invention is fully embodied in a single valve mechanism connected with the piston cylinder 3 but torpedo tubes, as generally constructed, 115 make it necessary to provide a valve mechanism on each side of the torpedo so it may be discharged from either the starboard or the port torpedo tube.

In Fig. 2 the letter "G" indicates the relative location of the opening in the torpedo body through which the gyro setter shaft is manipulated.

In Fig. 3 I have shown a slightly modified form which adapts the invention to operate 125 a well-known torpedo of a different type. In this form piston cylinder 103 is placed vertically to so position piston rod 118 that

when projected it will lift trigger "T" which, in this type of torpedo, corresponds with starting pin "P" in Fig. 2.

Fig. 4 shows how the gyro setting shaft 5 may be combined with my improved starting mechanism. In this modification elements 230, 231, 232, 233, 234, and 235 are substantially the same in construction and have the same function as elements 30, 31, 10 32, 33, 34, 35, of Fig. 1. Nozzle 230, however has the additional function of serving as a wrench, and is therefore made other than cylindrical to fit in a correspondingly shaped socket in valve casing 204. Valve 15 casing 204 is rotatably mounted in bracket 240 and connection 241. The openings 242 afford communication between the inside of valve casing 204 and cylinder 3 by way of connection 241 and pipe 2 as shown. Valve 20 plug 208, spring 210 and cap 211 correspond with and perform the same functions as elements 8, 10, 11 respectively in Fig. 1. 243 is the gyro setting shaft suitably connected with valve casing 204 so that they may be 25 rotated simultaneously.

Nozzle 230 is adapted to be inserted into valve casing 204 and both rotated to any extent desired. Gyro setting shaft 243 being non rotatably connected with valve casing 30 204 must also rotate, thereby, through intermediate mechanisms, well known to those skilled in the art, setting the gyro. As the gyro-setting mechanism is not a part of my invention it is not necessary to illustrate or 35 describe it.

Elements 223, 224, 225, 226, 227, 228, and 30 229 are identical in construction and function with elements 23, 24, 25, 26, 27, 28, and 29 in Fig. 1.

40 In the modification shown in Figs. 5, 6 and 7 valve casing 304 carries a rotary valve plug 308 having two passes or ports 353 and 354, at right angles to each other leading from a central longitudinal pass or port 355. 45 Either of the ports 353 or 354 may be put in alinement with a port 350 leading to air receiver 344. When it is desired to fill the receiver port 353 should be put in alinement with port 350 this will locate port 354 so 50 that it is closed by the blank wall of valve casing 304 and the opening through extension 315 will be closed by the blank wall of valve plug 308 and at such time air may be pumped into the receiver through a conduit 55 adapted to be connected with plug 308 by a screw threaded connection 349 in the bottom of wrench socket 351. In filling receiver 344, air is pumped through port 352, orifices in valve cage 348, port 355, port 353 and port 60 350. Preferably, when air sufficient to operate starting pin "P", once, is condensed in receiver 344, the conduit is disconnected. Escape of air from receiver 344 is prevented because the conical stop valve 345 will be

pressed into the seat provided for it, by the 65 expansion spring 347 surrounding valve stem 346, and also by the expansion of the air in receiver 344. However, if desired, the internal air pressure on stop valve 345 may be prevented by rotating valve plug 308 70 through an angle of forty-five degrees. The ports 353 and 354 being spaced ninety degrees apart it is obvious that a rotation of but forty-five degrees from charging position will so locate the ports 353 and 354 that they 75 will be closed by the blank walls of casing 304 thereby placing ports 353 and 354 out of alinement with port 350 leading to receiver 344, thus closing port 350 and preventing any back pressure against stop valve 80 345 by the compressed air in receiver 344.

Whenever port 353 is in alinement with port 350, port 354 is in alinement with the passage through extension 315 as shown in Figs. 6 and 7 and the air in the receiver 344 85 has an unobstructed passage to cylinder 3.

Elements 323, 324, 325, 326, 327, 328 and 329 are identical in construction and function with the elements 23, 24, 25, 26, 27, 28, and 29 in Fig. 1.

90 The modification shown in Figs. 8, 9 and 10 is designed to be operated by the "flask air" of the torpedo.

Valve plug 408 having a wrench socket 451 in its outboard end is seated in valve 95 casing 404. This valve plug has two ports 469 and 470 communicating with each other at the center of the plug and extending radially therefrom at an angle of ninety degrees and so located with reference to conduit 472 100 leading to the "flask" and conduit 471 in extension 415 leading to pipe 2 that communication between conduits 471 and 472 may be established or interrupted by rotating valve plug 408 through an angle of ninety 105 degrees.

Valve case 404 has an extension 406 through which projects a prolongation of plug 408, the protruding end of which being provided with teeth, forms a pinion 460 in 110 engagement with a rack 461. Upon the end of the rack 461, remote from pinion 460, a piston 462 is secured to operate in cylinder 468. Cylinder 468 is formed in an extension of valve casing 404. Between the head 115 of cylinder 468 and the free end of piston 462 an expansion spring 463 is placed. Extending from cylinder 468 and communicating therewith is a cylinder 467 in which the air tight piston 465 is located. Piston 465 120 carries a piston rod 464 projecting through a stuffing box toward piston 462 in cylinder 468. Between the other side of piston 465 and the head of cylinder 467 an expansion spring 466 is placed.

125 By means of an end wrench inserted into socket 451 plug 408 may be rotated through an angle of ninety degrees to establish com-

munication between conduits 471 and 472. On account of the engagement of pinion 460 and rack 461, when plug 408 is rotated, rack 461 and its attached piston 462 are moved longitudinally, spring 463 being compressed thereby. The movement of piston 462 is sufficient to carry it beyond piston rod 464, thereupon spring 466 expands and projects piston rod 464 under piston 462 thus locking piston 462 in its elevated position with unobstructed communication between the "flask" and cylinder 3 through conduit 471, cylinder 467 and pipe 2, as shown thereby operating starting pin "P". When pressure rises in cylinder 467 sufficiently to compress spring 466 piston rod 464 is withdrawn from engagement with piston 462, spring 463 expands carrying piston 462 and its attached rack 461 to normal position thereby 20 rotating pinion 460 and its attached plug valve 408 and interrupting the flow of air from "flask". The relief valve mechanism 424, 425, 426, 427, 428, and 429 then acts exactly the same as the corresponding elements 25 in Figs. 1 and 2.

The operation is as follows: Referring more particularly to Figs. 1 and 2, and assuming valve plug 8 is in normal position, as shown at the left in Fig. 1, the conical end of nozzle 30 is seated in the conical cavity in the outboard end of valve plug 8 and then thrust inwardly; plug 8, nozzle 30 and plunger valve 31 traveling together until they reach the point shown by nozzle 30 at the right in Fig. 1, whereupon air is turned into the conduit. The effect of this is to thrust plunger valve 31 forwardly carrying with it valve plug 8 beyond the opening into extension 15, uncovering openings 35 in plunger valve 31 and establishing communication between the source of power and pipe 2; valve 21 is swung from the dotted line position to the full line position, piston 17 and rod 18 are driven forwardly causing starting pin "P" to operate. The air passing from the source of supply into the conduit is under such high pressure that it may be shut off and nozzle 30 may be withdrawn almost instantly after the compressed air is admitted. Springs 10 and 34 expand as soon as the supply air is turned off and return valve plug 8 and plunger valve 31 to their normal positions. Air is allowed to escape from the pipe system continuously through the small port 28 but the loss is so slight it does not interfere with the instantaneous actuation of piston 17; furthermore as only two fifths of a second are required to secure full head way for the torpedo gyro spinning mechanism, after the forward action of piston 17 is completed, and as the full launching movement of the torpedo tube is effected in from 1 to 5 seconds thereafter, it is obvious that the loss of air through port 28 during the time the torpedo remains with-

in the tube may be safely neglected, while the torpedo is beginning its run the escape of air is continuous, quickly reducing the pressure in the pipe system sufficiently to allow spring 20 to return piston 17 to its normal position. Spring 25 in the relief system should be strong enough to overcome a pressure of approximately ten pounds to the square inch and spring 20 in cylinder 3 should be somewhat more powerful, so that 75 spring 20 will act before the leakage of air ceases and spring 25 will stop the leakage of air before sea water can enter.

To operate the modification shown in Figs. 5, 6, and 7 a suitable releasing wrench 80 is inserted into the socket 351 and given a turn of ninety degrees in a clock wise direction to establish an unobstructed passage from receiver 344 to cylinder 3; piston 17 and the piston rod 18 are projected instantly, driving starting pin "P" forwardly thus accomplishing the object sought. Leakage from the system goes on as in the preferred form.

In the operation of the modification 90 shown in Figs. 8, 9, and 10 plug valve 408 is given a quarter turn in a clockwise direction by a wrench inserted in a socket 451. The rotation of plug valve 408 establishes communication between the "flask" 95 and cylinder 3 and starting pin "P" is operated, but when the pressure is sufficient to compress spring 466 the air is automatically cut off as previously explained by the rotation of plug valve 8 to its normal position, the leakage of air then taking place as in the preferred form.

From the foregoing description it will be seen that I have provided an automatically operating mechanism which does away with the present crude manner of tripping the starting hook by a long rod manually manipulated or by the uncertain contacting of the hook with an inwardly projecting lug, in the torpedo tube, after the torpedo has received the impulse which discharges it and when a failure of the two parts to engage results in the total loss of a torpedo without any possibility of accomplishing the object for which it was intended. By 110 my mechanism the turbine driving and gyro-spinning mechanism will be started, invariably, if there is sufficient compressed air in the flask to drive them.

Torpedoes provided with my invention do not have the usual projecting hook or trigger which is sometimes inadvertently tripped. They are smooth bodied and can be shipped, fully charged, without providing the special devices torpedoes now require to prevent meddlers from tampering with them. It is practically an impossibility to operate a torpedo equipped with my invention excepting by special mechanism, designed for the purpose, including the nozzle 130

shown or an equivalent construction, and the handling of torpedoes on shipboard is thus made safe, no matter how awkward or excited the crew may be through the heat of battle.

Having thus fully described my invention, what I claim to be new, and desire to secure by Letters Patent of the United States, is—

1. In a torpedo provided with an element for starting the propelling mechanism and the steering control mechanism, the combination of a fluid operated element so located that when moved to operative position it will contact with and actuate the starting element of the torpedo, and mechanism to supply fluid under pressure to move said fluid operated element to operative position whereby the propelling and the steering control machinery of the torpedo will be started. 70
2. In a torpedo having a starting element, the combination of a fluid operated element so located as to contact with and operate said starting element, a conduit connecting a source of fluid under pressure with said fluid operated element and mechanism in said conduit for permitting and for stopping the flow of fluid to said fluid operated element. 75
3. In a torpedo having a starting element, the combination of a cylinder, a piston in said cylinder, a piston rod fixed to said piston and projecting through the head of the cylinder and so located that when the piston is operated the piston rod will contact with and actuate said starting element, a conduit connecting the cylinder to a source of fluid under pressure and a valve mechanism in said conduit for admitting operating fluid to the cylinder to actuate said piston and for stopping the flow of said operating fluid after the piston has been actuated. 80
4. In a torpedo provided with an element for starting the propelling mechanism and the steering control mechanism, the combination of a fluid operated element so located as to contact with and actuate the starting element, a conduit connecting the fluid operated element with a source of fluid under pressure, valve mechanism in the conduit for admitting operating fluid to the fluid operated element to actuate the starting element and for stopping the flow of operating fluid to the fluid operated element after the starting element has been actuated, and a relief port in the conduit for the escape of actuating fluid from the conduit to reduce the pressure sufficiently to permit the starting element of the torpedo to return to its normal position. 85
5. In combination with the starting element of a torpedo, means to positively displace the starting element, including a fluid actuated element whose movement is transmitted to the starting element. 90
6. The combination with a torpedo of a mechanism inclosed within the torpedo body for starting the propelling and the gyro-spinning machinery and means insertible through an opening through the torpedo-body to supply fluid under pressure for operating said mechanism whereby said machinery is actuated. 95
7. In a torpedo provided with a starting element, the combination of a cylinder having a piston therein for actuating said starting element, a conduit leading from said cylinder, a valve casing in said conduit, a valve plug therein and means connecting said valve casing to a source of power, said means including a nozzle for operating said valve plug when fluid is admitted to said nozzle. 100
8. In combination with a starting element of a torpedo, mechanism comprising a cylinder having a piston therein, a conduit connecting the cylinder with a source of power and a valve mechanism in said conduit, whereby the starting element is actuated by the piston when fluid under pressure is admitted into the cylinder by said valve mechanism. 105
9. In combination with a torpedo provided with a port or opening in the shell thereof, a valve casing within the torpedo body attached to said shell to register with said port or opening and a valve within the casing normally positioned to close the port or opening in said torpedo shell to exclude fluid therefrom. 110
10. In combination with a torpedo provided with a port or opening in the shell thereof, means properly positioned within the torpedo for actuating its starting element, a valve casing within the torpedo body attached to the shell to register with said port or opening, a valve within the casing normally positioned to close the port or opening in said torpedo shell, a conduit connecting said casing with said means for actuating the starting element of the torpedo 115 and a relief valve properly positioned to allow the escape of fluid under pressure from said conduit. 120
11. In a torpedo provided with a port or opening in the shell thereof, the combination of means for actuating the starting element of the torpedo, a valve casing within the torpedo body attached to said shell to register with said port or opening, a conduit connecting said casing to said actuating means and a valve within the casing normally positioned to close the entrance to said conduit. 125
12. In a torpedo provided with a port or opening in the shell thereof, the combination of a cylinder, a piston in said cylinder, a piston rod fixed to the piston and projecting through the cylinder head, a valve casing within the torpedo body attached to the torpedo shell to register with said port or 130

opening, a conduit for conducting fluid under pressure connecting said cylinder to said valve casing, and a controlling mechanism in said valve casing.

5. 13. In a torpedo provided with a port or opening in the shell thereof, the combination of a cylinder, a piston in said cylinder, means carried by said piston for actuating the starting element of the torpedo when

10 fluid under pressure is admitted to said cylinder, a valve casing within the torpedo body attached to the torpedo shell to register with said port or opening, a conduit for conducting fluid under pressure connecting said cylinder to said valve casing, a controlling mechanism in said valve casing for admitting fluid under pressure into said conduit and a relief mechanism through which said fluid under pressure in said conduit may 20 escape.

14. In a torpedo provided with a port or opening, the combination of a cylinder, a piston in said cylinder, means carried by said piston for actuating the starting element of the torpedo when fluid under pressure is admitted to said cylinder, a valve casing within the torpedo body attached to the shell to register with said port or opening, a conduit connecting said valve casing with said cylinder, a controlling mechanism in said valve casing for admitting fluid under pressure into said conduit, said mechanism including a valve normally positioned to exclude fluid from said conduit.

25 15. In a torpedo provided with a port or opening, the combination of a cylinder, a piston in said cylinder, means carried by said piston for actuating the starting element of the torpedo when fluid under pressure is admitted to said cylinder, a valve casing within the torpedo body attached to the shell to register with said port or opening, a conduit connecting said valve casing with said cylinder, a controlling mechanism in said valve 40 casing for admitting fluid under pressure into said conduit, said mechanism including a valve and means controlling its position whereby fluid is normally excluded from said conduit.

45 16. In a torpedo provided with a port or opening, the combination of a cylinder, a piston in said cylinder, means carried by said piston for actuating the starting element of the torpedo when fluid under pressure is admitted to said cylinder, a valve casing within the torpedo body attached to the shell to register with said port or opening, a conduit connecting said valve casing with said cylinder, a controlling mechanism 50 in said valve casing for admitting fluid under pressure into said conduit said mechanism including a valve and means controlling the position of said valve when subjected to the action of fluid under pressure.

55 17. The combination of two valve mecha-

nisms, a check valve box with which both valve mechanisms are connected, a check valve in said check valve box, a cylinder connected with said check valve box, a piston in said cylinder and a piston rod connected to said piston and projecting through the end of the cylinder.

18. The combination of two valve mechanisms, a check valve box with which both valve mechanisms are connected, a check valve in said check valve box, a cylinder connected with said valve box, a piston in said cylinder, a piston rod connected to said piston and projecting through the end of said cylinder and means for connecting either 80 valve mechanism with a source of power.

19. In a torpedo, the combination of a means for starting mechanism within the torpedo and means to control the operation of the starting means including a cylinder, 85 a piston therein, a conduit leading from the cylinder to the shell of the torpedo and a valve to normally close the entrance to the conduit from the exterior of the shell.

20. In a torpedo the combination of a 90 means for starting mechanism within the torpedo and means to control the operation of the starting means including a cylinder, a piston therein, a conduit leading from the cylinder to a source of fluid under pressure 95 and a valve to normally close the conduit and a tube leading from the valve to an opening in the torpedo shell through which the valve may be operated to admit fluid under pressure to the cylinder.

100 21. In a torpedo provided with a starting element, the combination of a cylinder, a piston in said cylinder for actuating said starting element, a conduit for conducting fluid under pressure to said cylinder from 105 a source exterior to the torpedo, a valve casing in said conduit and a valve plug in said casing normally positioned to exclude fluid from said cylinder.

110 22. The combination in a gyro spinning and torpedo propelling mechanism starter, of a valve mechanism, a conduit connecting said valve mechanism to said starter, a relief device in said conduit comprising a port, a valve for closing the port and a spring 115 for seating said valve.

120 23. In a torpedo, the combination of a cylinder, a piston therein, a spring to hold said piston in normal position, a valve casing, a conduit connecting the cylinder and the valve casing, a reciprocatable valve plug in the valve casing, a spring to hold the valve plug in normal position, a relief device in the conduit and means for reciprocating the valve plug whereby communication is established between the cylinder and a source 125 of power and the piston is projected for the purpose shown and described.

130 24. In a torpedo provided with a starting element the combination of a starting mecha-

nism including a cylinder, a piston therein for actuating the starting element and a conduit connecting the cylinder with a source of fluid under pressure; controlling mechanism in said conduit comprising a rotary valve casing having a valve plug therein and a gyro-setting shaft connected to said valve casing whereby when the valve casing is rotated the gyro-setting shaft is likewise rotated.

25. In a torpedo having a starting element, the combination of a cylinder having a projecting piston, a rotatable valve casing, a conduit connecting the cylinder and the 15 rotatable valve casing, a gyro-setting shaft connected with the rotatable valve casing, a valve in said valve casing to control the flow of fluid to the cylinder whereby the piston is actuated to operate the starting 23 element.

26. In a torpedo the combination of a

valve casing, a rotatable valve plug therein, an extension on said valve plug projecting through the valve casing, a pinion on said extension, a cylinder, a piston in said cylinder, a spring for actuating said piston, a piston rod attached to said piston and projecting beyond said cylinder, rack teeth on said piston rod in engagement with the pinion, a second cylinder, a piston in the second cylinder and a spring for projecting the piston in the second cylinder under the piston in the first cylinder to serve as a stop therefor.

In testimony whereof I have signed my name to this specification, in the presence of two subscribing witnesses.

GEORGE A. KNOX.
